O. M. WOLFF.
COUNTER PARTITION BRACKET.
APPLICATION FILED DEO. 19, 1913.

1,103,459.

Patented July 14, 1914.

UNITED STATES PATENT OFFICE.

OSCAR M. WOLFF, OF CHICAGO, ILLINOIS.

COUNTER-PARTITION BRACKET.

1,103,459.

Specification of Letters Patent. Patented July 14, 1914.

Application filed December 19, 1913. Serial No. 807,627.

To all whom it may concern:

Be it known that I, OSCAR M. WOLFF, a citizen of the United States of America, and a resident of Chicago, in the county of 5 Cook and State of Illinois, have invented certain new and useful Improvements in Counter-Partition Brackets, of which the following is a specification.

The main object of this invention is to 10 provide an improved form of bracket for glass counter construction having improved means thereon for supporting glass panel partitions.

An illustrative embodiment of this invention is shown in the accompanying drawings, in which—

Figure 1 is a perspective view of one end 20 of a counter showing the arrangement thereon of the bracket for supporting panel partitions. Fig. 2 is a transverse sectional elevation of the same. Fig. 3 is an end elevation of the bracket. Fig. 4 is an enlarged sectional detail taken on the line A—A of Fig. 2. Fig. 5 is an enlarged fragmentary 25 detail partly sectional as viewed from the plane of the line B—B of Fig. 2.

In the construction shown in the drawings, the bracket comprises an upright part 1 having a horizontal part 2 integrally 30 formed thereon at the upper end. A foot or pad 3 is integrally formed at the lower end of the upright part 1 by means of which the bracket is adapted to be secured to the counter or supporting member 4 by screws 35 or bolts 5. The upright part 1 of the bracket is preferably of T-shaped cross section, having a transverse flange 6 and a web 7. A clamping member, herein shown in the form of a plate 8, is adjustably mounted on 40 the outer face of the transverse flange 6 and adapted to engage the edges of adjacent vertical glass panels 9 and 10 between said plate and the outer face of the transverse flange 6. The clamping plate 8 is held in 45 place by means of screws or bolts 11 which have threaded engagement with the outer ends of the threaded apertures 13 extending through the web part 7 of the bracket. A second clamping member or plate 15 is ad- 50 justably mounted on the upper face of the horizontal part 2 of the bracket, being adapted to engage the edges of adjacent horizontal glass partitions between the plate 15 and the upper face of the horizontal part 55 2. The gripping faces of the clamping members 8 and 15 and the bracket are

padded with strips of felt, or other suitable material 14, so as to prevent injury to the edges of the panels.

In order to obtain a more rigid support 60 for transverse panel partitions 16, such as that shown in the drawings, a channel member 17 is secured to the inner face of the web part 7 of the bracket. The channel plate 17 is held in place by means of flat 65 headed screws 18 located in the inner ends of the threaded apertures 13, the heads of the screws being countersunk into the channel member. The channel member embraces the vertical edge of the panel 16 through- 70 out its entire height so as to form a rigid support therefor along the outer edge. The inner end of the clamping plate 15 is bent downwardly as at 19, and has a notch 20 formed therein so as to provide depending 75 shoulders 21 which are adapted to embrace the edge of the panel partition 16 adjacent to the inner end of the horizontal part 2. The foot 3 is provided with a recess 22 located in alignment with the web 7 of the 80 bracket and adapted to engage the lower outer corner of the panel partition 16 thereby avoiding the necessity of grinding that corner of the glass in order to obtain a close fit to the bracket along its outer edge. A 85 channel member 23 may be secured to the counter 4 in alignment with the bracket, so as to embrace and support the lower edge of the panel partition 16. This channel member is secured to the counter abutting 90 against the foot 3, and having the channel in alignment with the recess 22 in the foot 3.

Although but one specific embodiment of this invention has been herein shown and described, it will be understood that some of 95 the details of the construction shown may be altered or omitted without departing from the spirit of this invention as defined by the following claims.

I claim:

1. The combination of a bracket of T-shaped cross-section, means for securing said bracket to a counter, said bracket having threaded apertures extending through the web part thereof, a member mounted on the outer face of the transverse part of said bracket, fastening means engaging the outer ends of said apertures and adapted to secure said clamping member in position to engage the edges of adjacent glass panels between 110 said member and the face of said transverse part, a channel member secured to the inner

face of the web part of said bracket and adapted to embrace the edge of a transverse panel, and other fastening means engaging the inner ends of said apertures and adapted 5 to secure said channel member to said bracket.

2. The combination of a bracket having a horizontally disposed part at the upper end thereof, a foot on the upright part of said bracket adapted to be used for securing said bracket to a counter, a clamping member mounted on the outer face of the upright part of said bracket and adapted to engage the edges of adjacent vertically disposed glass panels between said member and the face of said bracket, a second clamping member mounted on the upper face of said horizontal part and adapted to engage the edges of adjacent horizontally disposed glass panels between said member and the upper face of said horizontal part, a 10 channel member secured to the inner face of the upright part of said bracket and adapted to embrace the edge of a transverse vertical panel, and shoulders depending from said second clamping member and embracing the 15 adjacent edge of said transverse panel.

20 between said member and the upper face of said horizontal part, said foot having a recess formed therein adapted to receive the lower corner of a transverse panel, and depending shoulders on said second clamping member 25 adapted to embrace the adjacent edge of said transverse panel.

3. The combination of a bracket having a horizontally disposed part at the upper end thereof, a foot on the upright part of said bracket adapted to be used for securing said bracket to a counter, a clamping member mounted on the outer face of the upright part of said bracket and adapted to engage the edges of adjacent vertically disposed 30 glass panels between said member and the face of said bracket, a second clamping member mounted on the upper face of said horizontal part and adapted to engage the edges of adjacent horizontally disposed glass panels between said member and the upper face of said horizontal part, and a channel member secured to the inner face of the upright part of said bracket and adapted to embrace the edge of a transverse vertical panel the outer end of said second 35 clamping member being bent downwardly and having a notch formed therein adapted 40 to provide a pair of shoulders embracing the adjacent edge of said transverse panel.

45 said horizontal part of said bracket and adapted to embrace the adjacent edge of said transverse panel.

4. The combination of a bracket having a horizontally disposed part at the upper end thereof, means for securing said bracket to a counter, a clamping member mounted on the outer face of the upright part of said bracket and adapted to engage the edges of adjacent vertically disposed glass panels between said member and the face of said bracket, a second clamping member mounted on the upper face of said horizontal part and adapted to engage the edges of adjacent horizontally disposed glass panels between said member and the upper face of said horizontal part, a 50 channel member secured to the inner face of the upright part of said bracket and adapted to embrace the edge of a transverse vertical panel, and shoulders depending from said second clamping member and embracing the 55 adjacent edge of said transverse panel.

5. The combination of a bracket having a horizontally disposed part at the upper end thereof, means for securing said bracket to a counter, a clamping member mounted on the outer face of the upright part of said bracket and adapted to engage the edges of adjacent vertically disposed glass panels between said member and the face of said bracket, a second clamping member mounted on the upper face of said horizontal part and adapted to engage the edges of adjacent horizontally disposed glass panels between said member and the upper face of said horizontal part, and a channel member secured to the inner face of the upright part of said bracket and adapted to embrace the edge of a transverse vertical panel the outer end of said second clamping member being bent downwardly and having a notch formed therein adapted 70 to provide a pair of shoulders embracing the adjacent edge of said transverse panel.

Signed at Chicago this 17th day of December 1913.

OSCAR M. WOLFF.
